UNITED STATES PATENT OFFICE.

WILLIAM F. EMERSON, OF WILLIAMSVILLE, NEW YORK.

DEVICE FOR HONING INTERNAL CYLINDRICAL SURFACES.

Application filed January 4, 1923. Serial No. 610,617.

This invention relates to the art of finishing of the cylindrical bores of motor cylinders and consists of an improved milling or honing tool of an improved construction and arrangement particularly adapted for finishing of the surfaces of the cylinder bores with a more highly and accurately finished surface than has been obtained by the use of tools as heretofore used for the purpose.

In my co-pending application, Serial No. 541,338 I have illustrated a desirable type and design of portable milling or honing tool employing honing stones, radially positioned and arranged to act upon the internal peripheral surface of a cylinder bore under pressure whereby, upon rotation of the tool, the cylinder wall is honed to produce a smooth and polished surface. A tool of this type and particularly of the portable design, as illustrated, is especially well adapted for the refinishing of worn and scored cylinders in connection with the replacing of the pistons with so called over-sized pistons which is the customary practice. With particular reference to this reboring operating upon worn cylinders it has been demonstrated that a particular difficulty is presented by the fact that under the conditions of wear the cylinder walls are often found to be tapered or inclined from parallel relation with the upper portion of the cylinder wall against which the piston rings bear having an enlarged diameter relative to the lower portion of the wall engaged by the piston or vice versa.

A particular object of my present improvements is to provide a honing tool adapted in its action to eliminate the taper of the cylinder bore and to insure that the finished cylindrical surface shall have its curved walls in accurate parallel relation whereby the diameter of the bore shall be uniform throughout. To this end an important feature of the present invention consists of an improved arrangement and construction whereby the honing stones are so supported that in their various positions of adjustment the active surfaces thereof shall be at all times maintained in parallel relation.

Additional important features of the present improvements consist in the arrangement whereby the adjustment of the supporting trays is effected from the upper or top side of the tool which allows with advantage of

the adjustment thereof being made after the tool has been inserted within the bore; of an improved flexible connection between the hone body and the driving handle or supporting shaft of a detachable type which allows of conveniently and readily securing the driving handle to the tool after the latter has been positioned within the cylinder bore and an improved construction and arrangement for detachably securing the stones within their supporting trays in a manner which facilitates the removal thereof and which allows of the stones being adjusted to change the active surfaces. The latter feature is of further advantage in providing for convenience in removing of the stones for the redressing of the active surfaces and in facilitating the replacing of the stones as may be required.

The described and other valuable features and advantages of my invention will be understood by reference to the accompanying drawing wherein like reference numerals are applied to the corresponding parts in the several views.

Referring to the drawing:

Fig. 1 is a central, vertical, sectional view of a desirable embodiment of the features of my invention.

Fig. 2 is a view thereof in side elevation.

Fig. 3 is a horizontal, cross-sectional view taken on line 3—3 of Fig. 1.

Fig. 4 is a plan view illustrating the operating shaft in position for assembling.

Figs. 5 and 6 are plan views, respectively, of the securing plate and the body member illustrating the arrangement for coupling to the operating shaft.

Fig. 7 is an enlarged cross sectional view through one of the tray members, and

Fig. 8 is a detailed longitudinal section through a portion of a tray or carrier member, illustrating the means for securing the stones in position.

In the drawings there is illustrated an approved embodiment of the features of my invention wherein 1 indicates the supporting or body member of the tool which is of general cylindrical form and adapted to support and provide bearings for the several movable parts of the completed tool. The body 1 of the tool is of a size and of suitable diameter to allow of its being received bodily within the cylindrical bore to be acted upon. This supporting member 1 is further desirably arranged to be supported upon

and rotated by an operating shaft having a suitable flexible connection and driven by a portable type of driving motor. For this purpose the operating shaft 2, or driving handle, is provided and arranged at its lower extremity to have coupling arrangement with the tool body 1 whereby it will support the tool body to transmit rotary motion thereto. The upper end of the operating shaft or driving handle 2 is suitably reduced at 3 to be received by the chuck of a portable drill motor or similar portable motor. The arrangement is accordingly such that it permits of the tool being manually supported within the cylindrical bore by the operator and to be vertically reciprocated therein while being rotated at a suitable speed under the influence of the power derived from the motor armature shaft.

An important feature of the present invention consists in the specific form and arrangement of the connecting means affording the support and driving connection between the tool body and the operating shaft 2. In accordance therewith the operating shaft 2 is provided at its lower extremity with a ball enlargement 4 fitted within a suitable socket or opening 5 formed in the upper end portion of the supporting member 1 of the tool. The lower portion of the socket 5 is formed with opposite spherical surfaces 6-6 described by arcs concentric with the longitudinal axis of the tool and of radii generally complementary to the ball enlargement 4 to provide a bearing seat therefor. This socket 5 is also formed, as shown, with opposite radial extensions or openings 7-7 within which are received key extensions 8-8 formed upon the ball enlargement 4 of the operating shaft 2, the purpose of which is to rotatably secure the supporting member 1 to the operating shaft 2 whereby they will rotate in unison. A cover or securing plate 9 is suitably attached to the upper end of the body member 1 by means of screws, as shown, and is arranged to overlie the key extensions 8 to oppose longitudinal separation of the tool and driving handle and withdrawal of the ball engagement from within the socket under normal operating conditions. The arrangement, as described, provides a flexible driving connection or coupling between the tool body 1 and the operating shaft which allows of relative axial deflection of said members which is particularly desirable and advantageous in avoiding lateral strains and vibration of the tool in the milling operation as it allows of the milling tool proper to be self-aligning with relation to the axis of the bore being acted upon.

Incidental to further features of this coupling connection an additional and important advantage obtained is that the connected parts are readily separable. The resulting arrangement conveniently allows of the parts being detached to permit of adjustment of the parts of the honing tool while the tool proper is positioned within the bore of the cylinder. For this purpose (as best shown in Fig. 4) the radial enlargements or oppositely extended openings 7, are annularly enlarged to permit a partial rotation of the key members 8 therein and the cover or end closing plate 9 is formed with a central enlarged circular opening 1 of a diameter sufficient to allow the passage of the ball enlargement 4 therethrough and is provided at one side thereof only with a radial extension to said opening in the form of a key slot 11. This key slot is of a size merely sufficient to allow the passage of the key element 8 therethrough. The key opening 11, as will be noted, is positioned above the angularly enlarged socket extension 7, and at one end thereof as considered angularly, and which for reference may be termed the rear end of the opening as defined by its forward and rearward vertical walls 12 and 13. As a result thereof, with the key element 8 in angular position of registration with the key slot 11, upon tilting of the operating shaft the key element 8 may be withdrawn from within the socket and with the shaft thus positioned at a wide angle to the longitudinal axis of the tool body, as indicated in Fig. 2, the ball enlargement and opposite key extension 8 may be withdrawn through the circular opening 10 and the parts fully separated. In similar manner the parts are assembled and upon giving the shaft a partial revolution in clockwise direction, as indicated in Fig. 4, the key elements 8 will assume the forward engaging position within the opening 7 in which normal and operating position the parts are non-separable. This described arrangement is particularly desirable in that the separation of the parts is permitted only upon tilting of the operating shaft to the wide angular position indicated and in all other positions the parts cannot be longitudinally separated irrespective of whether or not the key 8 is in vertical registration with the key slot 11. There is thus provided a detachable and flexible connection which allows of coupling by simple manipulation and without removal of parts and which under normal operating conditions provides an effective driving and supporting connection.

The supporting member 1 below its upper end or socket portion, is formed with an enlarged opening 15 the wall of which may be circular in form and concentric with the central longitudinal axis of the tool. The member 1 is accordingly formed for the major portion of its length of an annular wall which is provided, as shown, with longitudinally extending, elongated and parallel guide slots 18 of which four are shown

spaced equi-distantly around the circumference of the tool. The side walls of the oppositely positioned guide slots 18 are parallel to a central vertical plane through the 5 axis of the tool and form guideways to which are fitted carrier members or trays 20 adapted to be radially adjusted therein. The carriers 20 have their outer side walls 21 formed for guiding engagement with the 10 guide slots and are adapted to receive and support the elongated honing stones 22 desirably rectangular in cross-section and formed of suitable carborundum or like composition.

15 The honing stones 22 are desirably supported within the pans or carriers 20 in a resilient and yielding manner so that in operation they will act under spring pressure against the surfaces being acted upon. For 20 this purpose the central portion 25 of the rear wall of the tray or carrier is formed parallel to the longitudinal axis of the tool and is provided with socket depressions 26 to receive therein coil springs 27 arranged to 25 exert an outward pressure against the honing stones 22. As indicated each of the trays is provided with two compression springs 27 to act upon the stones, but as will be understood a single compression spring or 30 equivalent resilient means may be employed for the purpose. A particularly important feature of the present invention consists in the provision or incorporation with the radial acting means, of means for equalizing 35 or controlling the movement of the stones under outward pressure whereby the movement will be uniform with respect to the opposite ends of the stone for the purpose of at all times maintaining the outer or active 40 surfaces of the stones in true parallel relation. For the purpose, as here shown, there is provided within each tray a pressure transmission plate or tension plate 28 interposed between the compression springs 27 45 and the honing stones 22. As best illustrated in Figs. 3 and 7, the transmission plates 28 are hingedly or pivotally secured within the trays at one longitudinal edge thereof within a suitable longitudinal slot or 50 recess 29 formed in one inner wall of the tray and extending parallel to the longitudinal axis of the tool. The transmission plates 28, as shown, are rounded upon their longitudinal edges and the slots 29 are correspondingly rounded whereby the plate will 55 freely pivot therein. For securing the plates 28 to pivot within the slots 29 they are, as shown, provided with openings 30 to receive the small retaining blocks or shoulders 31 60 attached to the rear wall of the tray by being riveted thereto. The plates are thereby supported and confined to move in a fixed plane under the influence of the compression springs bearing thereagainst in consequence 65 of which the radial movement of the honing stones is governed so as to be uniform throughout their length and thereby maintain in all positions the desired parallel or true vertical position of their active surfaces. This feature is of great importance 70 as related to the successful operation of the tool in the reborning of worn cylinders in that it insures of obtaining a refinished bore having its walls accurately parallel or longitudinally of uniform diameter. The transmission or tension plates 28, in acting to 75 maintain parallel at all times the honing surfaces, permit of refinishing cylinder bores which have been worn to a tapered condition (wherein the curved surfaces are longitudinally inclined) so as to correct the alignment of the walls rather than to follow up the inclination during the honing action as has been the fault of honing tools as heretofore used. This feature is of further importance in preventing the tilting of the stones during the honing action as would otherwise result under conditions where hard spots or regions are encountered in 80 the surfaces being acted upon.

85 Suitable means are provided for retaining the honing stones 22 within the supporting trays 20. In accordance with the present improvements each of the trays is provided at one end of the wall with an inwardly projecting integral lug or stop 35 received within an annular enlarged opening 36 formed in the end of the honing stone and at its opposite end the tray is provided with a suitable yielding retaining means adapted to 90 permit of readily withdrawing the stone as desired. The latter means, as here shown, consists of a suitable socket member 37 fitted to the end wall of the tray and formed with an inwardly directed recess or opening 38 95 within which is positioned a compression spring 39 bearing upon a yieldable stop or ball 40 confined within the socket by turning or punching inwardly of portions of the member 37 to a degree which permits of the ball partially projecting therebeyond. The adjacent end of the honing stone is formed with an enlarged annular opening 41 which may be of the concave form, as shown, to 100 receive the ball. The stone 22 is thereby 105 yieldingly retained within the tray in a manner permitting of its being readily removed. To facilitate the latter the side walls of the trays are suitably recessed at 43—43 adjacent 110 their upper ends to allow of grasping the stones with the fingers to effect their removal. The enlarged openings 36 and 41 in the ends 115 of the stones are proportioned to allow of the desired radial movement of the stones within the trays to permit of the stones acting under the spring pressure in the honing operation.

120 The described method of securing the plates 28 within the trays is such as to limit or determine the extreme outward movement im- 125

130

parted thereby to the stones under the influence of the springs 27 and this extreme movement, as will be understood, is limited to preclude of moving the stones outwardly beyond a position whereby they are retained by means of the yielding catch 40. The described retaining means for the stones is desirable and advantageous in facilitating the removal of the stones without requiring special tools therefor. This permits of readily substituting stones of finer grade or abrasive texture for finishing the honing operation and further permits of readily changing the position of the stones within the holders to renew the acting surfaces whereby the several surfaces of the stones may be employed with resulting economy.

There is further incorporated with the described construction means for adjusting the carrier members for the purpose of adapting the tool for the regrinding of cylinder bores of varying diameter. The arrangement provided for this purpose in the construction as illustrated in Figs. 1 and 3 consists in forming the carrier member or tray 20 with the end portions 50 of its rear wall reversely and inwardly inclined. The inner or bearing surfaces of the inclined walls 50 are engaged by the parallel external inclined surfaces of wedges 52. These wedges are rectangular in cross-section with outer inclined walls and are centrally threaded for screw engagement with the axially extending, reversely threaded adjusting screw 55. The adjusting screw is suitably journaled at its respective ends at 56 in the upper wall of the supporting member and in the bearing lug 57 threaded to the lower end of the member 1. It is provided at its upper extremity with the manipulating slot 59 for adjustment by means of a screw-driver. The inclined walls 50 of the pan or carrier 20 are provided with longitudinal guide slots 60 to which are fitted guiding studs 61 threaded to apertures in the adjusting wedges 52, the studs being loosely fitted within the slot and the heads thereof acting to confine the carriers from outward movement with relation to the wedges. As will be obvious from the construction disclosed upon rotation of the screw 55 the wedges 52 will relatively advance or recede and thereby move the carriers radially outwardly or inwardly to varied positions of adjustment. The described construction in desirable manner provides for the radial adjustment of the tracys by manipulation from the upper end of the tool. This is effected upon the uncoupling or separation of the driving shaft 2 from the holder 1 in the convenient manner, as heretofore described. Access is then permitted for adjusting of the screw 55 by means of a screw-driver or other suitable tool through the aperture 9 and socket 7 which allows of making the adjust-

ment with the honing tool positioned within the cylinder bore to be acted upon.

Having described my invention I claim:

1. A device of the character described comprising a suitable supporting member, a series of radially disposed carrier members upon the supporting member, honing stones fitted within the carrier members, means within the carriers adapted to impart yielding outward pressure to the stones and means interposed between the pressure means and the stones and operative to maintain the stones in constant parallel relation throughout their expansive movement, said means consisting of a transmission plate having an elongated bearing upon the inner surface of the stone and hingedly connected to the carrier to be movable only in a fixed plane.

2. A device of the character described comprising a suitable supporting member, a series of radially disposed carrier members carried by the supporting members, honing stones fitted within the carrier members to be movable radially therein, compression springs positioned within carriers to exert a yielding outward pressure against the stones, a pressure transmission plate interposed between the stones and said springs, said transmission plate having an elongated bearing against the inner side of the stone and being hingedly supported within the carrier member to move in a fixed plane so as to maintain the stones constantly in parallel relation.

3. A device of the character described comprising a suitable supporting member, a series of radially disposed carrier members carried by the supporting members, honing stones fitted within the carrier members to be movable radially therein, compression springs positioned within the carriers to exert a yielding outward pressure against the stones, a pressure transmission plate having an elongated bearing against the inner side of the stone and being hingedly supported within the carrier member to move in a fixed plane so as to maintain the stones constantly in parallel relation and means operative to adjust the carriers radially in unison for varying the effective diameter of the device.

4. A device of the character described comprising a suitable supporting member, a series of honing stones radially positioned therein and supported to be expansible under a yielding pressure, a supporting and driving shaft therefor and a flexible connection between said shaft and the supporting member, said connection being formed to permit separation or uncoupling when moved to an extreme angular position only, substantially as described.

5. A device of the character described comprising a supporting member, a series of

radially disposed carrier members upon the supporting member, honing stones fitted to the carriers and supported to be radially expandable therein and means to retain the 5 stones within the carriers comprising yieldable stops positioned to engage the stones, substantially as described.

6. A device of the character described comprising a supporting member, a series of 10 radially disposed carrier members upon the supporting member, honing stones fitted to the carriers and supported to be radially expandable therein and retaining means for the stones comprising rigid stops within the 15 carriers to engage the stones within enlarged recesses therein at one end of the carriers and yieldable stops fitted within the carriers to similarly engage the stones at the opposite 20 ends of the carriers, substantially as described.

7. A device of the character described comprising a supporting member, a series of radially disposed carrier members upon the supporting member, honing stones fitted 25 within the carrier members, means within the carriers adapted to impart yielding outward pressure to the stones, means interposed between the pressure means and the stones and operative to maintain the stones in constant parallel relation throughout their expansive movement consisting of a transmission 30 plate bearing upon the inner surface of the stone and hingedly connected to the carrier, retaining means for the stones consisting of inwardly directed stops, provided 35 at one end of the carriers and positioned within enlarged openings in the stones at one end thereof and ball stops fitted to sockets in the opposite ends of the carriers, compression 40 springs within the sockets positioned to act upon the ball to hold the balls under yielding pressure in position of enlargement with the stones within enlarged openings and said carrier members having their 45 side walls cut away adjacent the yielding stops to give access for grasping the stones whereby they may be readily withdrawn from the carriers.

8. A device of the character described 50 comprising a suitable supporting member, a series of radially disposed carrier members carried by the supporting members, honing stones fitted within the carrier members to be capable of outward or radial movement 55 therein, compression springs positioned within the carriers to exert a yielding outward pressure against the stones, a pressure transmission plate having an elongated bearing against the inner side of the stone and having a pivotal connection with the carrier member so as to be movable in a fixed plane, said connection comprising an elongated slot 60 in the wall of the carrier within which the longitudinal edge of the plate is fitted and 65 means for holding the plate within the slot

consisting of retaining shoulders affixed to the carrier and formed to overlie portions of the plate, substantially as described.

9. A device of the character described comprising a suitable supporting member, a 70 series of radially disposed carrier members upon the supporting member, honing stones fitted within the carrier members, means within the carriers adapted to impart yielding outward pressure to the stones, means 75 interposed between the pressure means and the stones and operative to maintain the stones in constant parallel relation throughout their expansive movement, and means operative to adjust the carriers radially in 80 unison for varying the effective diameter of the device.

10. A device of the character described comprising a suitable supporting member, a series of radially disposed carrier members 85 upon the supporting member, honing stones fitted within the carrier members, means within the carriers adapted to impart yielding outward pressure to the stones and means interposed between the pressure means and the stones and operative to maintain the stones in constant parallel relation throughout their expansive movement, said means consisting of a transmission plate having an elongated bearing upon the inner surface 90 of the stone and hingedly connected to the carrier to be movable only in a fixed plane and means operative to adjust the carriers 95 radially in unison for varying the effective diameter of the device. 100

11. In a cylinder grinder the combination with a rotatable block and a radially adjustable member therein, of a radially adjustable stone, a pivotal member extending longitudinally of and bearing against the inner side of said stone, and spring means for holding said pivotal means in contact with the stone. 105

12. In a cylinder grinder, the combination with a rotatable block and a radially adjustable member therein, of a radially adjustable stone, a member extending longitudinally of the inner side of the stone and pivoted at one side thereof and having the other side free, and a plurality of springs bearing 110 against the free side of said pivotal member to hold the stone extended uniformly from end to end. 115

13. In a cylinder grinder, the combination with a rotatable block having a plurality of 120 longitudinally radial slots and a common central passage connecting with said slots, holders slidably arranged in said slots having bevelled inner surfaces, adjustable tapered members engaging said bevelled surfaces and adapted to move said holders in uniform and equal adjustment, stones adjustably arranged in said holders, pivotal members within said holders bearing uniformly throughout the length of the inner 125 130

side of the stones, and spring means for holding said pivotal members against said stones.

14. A cylinder grinder, comprising a block having a plurality of radial slots, stone holding members slidably arranged in said slots, said members being recessed longitudinally, plates extending longitudinally within the recesses of said holders and pivoted at one side thereof, a plurality of coil springs bedded in the bottom of the recesses and pressing outwardly against the free portion of the pivotal plate, stones slidably retained in said recesses and engaging said pivotal plates, and means for limiting the radial movement of said stones.

Signed at Buffalo in the county of Erie and State of New York this 8th day of December A. D. 1922.

WILLIAM F. EMERSON.
